CLAIM

The ornamental design for a access system keypad housing,
as shown and described.

DESCRIPTION

FIG. 1 illustrates a perspective view of a access system keypad housing;

FIG. 2 illustrates a front view thereof;

FIG. 3 illustrates a right-side view thereof;

FIG. 4 illustrates a left-side view thereof;

FIG. 5 illustrates a top view thereof;

FIG. 6 illustrates a bottom view thereof; and,

FIG. 7 illustrates a back view thereof.

The broken lines shown represent unclaimed subject matter
and form no part of the claimed design.
